UNITED STATES PATENT OFFICE

MARK C. DE WOLFE, OF OAKLAND, CALIFORNIA

TOWERLESS HOISTING AND CONVEYING DEVICE

Application filed March 26, 1928. Serial No. 264,584.

Under the gravity system of conveying concrete, it is necessary to erect a tower which must be several hundred feet high if it is desired to convey the material quite a distance from the place where it is mixed to the place where it is poured into the forms. This tower must be held against swaying or bending by guy wires. It is also necessary to place a man up in this tower and to keep him there during the entire operation of the device in order that he may control the flow of concrete from the receiving hopper and to see that the hoisting bucket is delivering the concrete contained therein into the receiving hopper.

On especially large jobs, it is sometimes desirable to move the tower to a new location after all the forms around the old location have been filled. This is an extremely difficult thing to do, because as soon as one or more guy wires connected to the tower are loosened, the pull upon the tower by the other guy wires causes the tower to buckle. When once this takes place, it is practically impossible to again straighten the tower. When it is considered that towers cost in the neighborhood of \$60,000.00, it will be seen that the loss entailed by the movement of a tower to a new location is considerable should the tower become bent out of shape during its movement.

The principal object of the present invention is to provide a towerless hoisting and conveying device which dispenses with the operator as employed in the usual tower, which eliminates practically all of the guy wires, and which permits the point at which the concrete is mixed and first hoisted to the gravity chutes to be readily moved without the necessity of moving a tall cumbersome tower.

A further object of my invention is to provide a device of the type described that has means for quickly changing the elevation at which the hoisting bucket dumps its contents into the receiving hopper. I further provide means for causing the bucket to dump into either one of two hoppers, and the frame supporting these hoppers may be swung at right angles for permitting the hoisting

bucket to deliver its contents at any one of four places radially spaced about the bucket.

Other objects and advantages will appear in the following specification, and the novel features of the device will be particularly pointed out in the appended claims.

My invention is illustrated in the accompanying drawing forming a part of this application, in which

Figure 1 is a front elevation of the device, 60 a portion of the hopper-carrying frame being shown in section for clarity;

Figure 2 is a section along the line 2—2 of Figure 1;

Figure 3 is a section along the line 3—3 of Figure 2;

Figure 4 is an enlarged sectional view of a portion of the device;

Figure 5 is a section along the line 5—5 of Figure 4; and

Figure 6 is a top plan view of a portion of the device.

Assume that concrete for a dam is to be poured, and that the bottom of the dam lies in a plane indicated by the reference numeral 1 (see Figure 1), and that the sides of the ravine or other hollow in which the dam is to be built extend upwardly from the bottom 1 to approximately points lying substantially level with a supporting cable 2. With my device, anchors (not shown) are disposed at the sides of the gulley or hollow at a height which is higher than the highest point of the dam. The supporting cable 2 is stretched between these two anchoring points. It is obvious that my device can be used for building construction bridges, factories, and in fact anything where it is desired to pour large quantities of concrete or other material.

Upon the supporting cable 2 I mount a carriage 3 that is substantially square in plan view (see Figure 6.) This carriage has rollers 4 that ride upon the cable 2. The means for moving the carriage along the cable consist of a line 5 connected to the carriage at 6 and a line 7 connected to the carriage at 8. These lines may be wrapped around drums operatively connected to donkey engines or other suitable power source, and a tightening of one line and a slackening in the other will 100

move the carriage 3 along the cable 2 in the desired direction. The movement of the carriage 3 only takes place when it is desired to change the point at which concrete is dumped into gravity chutes.

It should be noted at this point that the present case does not show gravity chutes, because this is the subject matter of a co-pending application. The present case shows 10 a means of delivering concrete from a mixing point to a gravity chute. It further shows means for changing the point of delivery to the chute at will.

The carriage 3 forms the top of a towerless frame, and this frame takes the place 15 of the standard tower. I dispose guide cables 9 and 10 between the carriage 3 and the ground 1. These cables are connected to the carriage at 11 and 12, and extend through 20 sheaves 13 and 14 and thence to anchoring means 15 and 16. Turn-buckles 17 and 18 take up any slack in the cables 9 and 10. The sheaves are secured to foundation blocks 19 and 20. The turn-buckles 17 and 18 take up 25 the slack in the cables 9 and 10 and draw them taut enough to act as guides for a hoisting bucket 21.

Reference to Figures 1 and 4 show how the cables are covered with sectional sleeves 22 30 and 23. I have shown sleeves 22 in Figure 4, and it will be noted that each sleeve has a reduced portion 24 that fits into an adjacent sleeve. This provides a smooth exterior. The same is true with the sectional sleeves 35 23. The sleeves 22 are held in adjusted position by lock screws 25 and the sleeves 23 by lock screws 26, or other suitable fastening means. The sleeves extend substantially from the top of the cables 9 and 10 to the bottom thereof.

Upon the sleeves 22 and 23 I slidably 40 mount a hopper-carrying frame 27. This frame supports two receiving hoppers 28 and 29. The frame is carried by a hoisting line 30 45 (see Figure 1) that is passed through a block and tackle 31, the block and tackle in turn being connected to the top of the frame. The frame has openings 32 that receive the sleeves 22 and 23. A winding or unwinding 50 of the line 30 will raise or lower the frame 27.

The hoisting bucket 21 is designed to be raised up to the frame 27 and then to be 55 swung about its pivot 33 (see Figure 2) into a dumping position where it will discharge its contents into the hopper 28. The bucket carries a projection 34 that rides into a channel iron 35, and further movement of the bucket will swing it into the dotted-line position shown in Figure 2. When it is desired 60 to dump into the hopper 29, the position of the bucket 21 is reversed and then the projection 34 will be guided by a channel iron 36.

The bucket 21 is pivotally carried by a bail 37 (see Figure 1). This bail has each leg 65 portion thereof constructed of two channel

irons 38 and 39 that face each other (see Figure 5). Collars 40 comprising two half portions are disposed between the channel irons 38 and 39, and are secured in place by bolts 41. In Figure 1 I have shown two collars in each leg of the bail.

The legs of the bail are secured together by a bolt 42 and are held in spaced relation by a sleeve 43 mounted upon the bolt. The pivot point of the bucket 21 consists of the bolt 75 33 that has its ends secured to the bail 37. A protecting sleeve 43 is mounted upon the bolt.

The bucket is raised and lowered by a hoisting line 44 (see Figure 1), this line being 80 passed over sheaves 45 and 46, its end being secured to the bail 37 at 47.

From the foregoing description of the various parts of the device, the operation thereof may be readily understood.

The drawing illustrates the device erected 85 at approximately the center of the hollow in which the dam or other piece of masonry is to be erected. All of the working parts are supported by the cable 2, hoist lines 30 and 44, guide cables 9 and 10, and guy wires 48. Figure 3 shows that four guy wires 48 extend from the corners of the frame 27. These are the only guy wires necessary in the whole apparatus.

As fast as necessary, the frame 27 is raised 90 by means of the hoist line 30 in order to increase the height at which the concrete enters the gravity chutes. The chutes (not shown) lead from either the hopper 28 or the hopper 29. From these points the chutes convey the material to the forms. The hopper 28 permits concrete to be poured in all the forms to one side of the frame 27, while the hopper 29 takes care of the opposite side. The bolt 33 is temporarily removed and then reinserted 95 after the bucket has been turned in its position when delivering concrete to the hopper 29 instead of the hopper 28.

It is possible to swing the frame 27 at right angles. When this is done, the cables 9 and 10 are connected to points 49 and 50 on the carriage 3 (see Figure 6).

When moving the device to a new position, it is merely necessary to slacken the guy wires 48 and disconnect the cables 9 and 10 from their anchors 15 and 16. The entire device can now be moved along the cable 2 by means of the lines 5 and 7. The foundations 19 and 20 may be placed at the new position, or new foundations may be formed at this point. It will be seen that there is no tendency of any buckling when the guy wires 48 are released, because the entire mechanism is suspended from the cable 2. In place of a large number of guy wires necessary to support a 105 tower, I use only four.

When the pouring operation has been completed, the four guy wires 48 may be disconnected and the cables 9 and 10 loosened from their anchors and the device can be moved 110

away, leaving an entirely clear space for other building operations to follow. With the standard type of construction, a multitude of guy wires extend in every direction and hinder further building operations.

5 Although I have shown and described one embodiment of my invention, it is to be understood that the same is susceptible of various changes, and I reserve the right to employ such changes as may come within the scope 10 of the appended claims.

I claim:

1. A towerless hoisting and conveying device comprising a supporting cable, a carriage movable on said cable, vertical guide cables carried by said carriage, hoppers adjustable along the length of said vertical cables, and a bucket movable along said vertical cables for conveying material to said 20 hoppers.

2. A towerless hoisting and conveying device comprising a supporting cable, a carriage movable on said cable, vertical guide cables adjustably carried by said carriage, a 25 frame adjustable along the length of said vertical cables, hoppers carried by said frame, and a bucket movable along said vertical cables for conveying material to said hoppers.

30 3. A towerless hoisting and conveying device comprising a supporting cable, a carriage movable therealong and supported thereby, means for moving said carriage, guide cables depending from said carriage, 35 material-receiving means adjustable along the length of said guide cables, and a bucket movable along said guide cables for delivering material to said receiving means.

4. In a device of the type described, guide 40 cables, sectional sleeves covering said cables and providing a smooth exterior, a bail movable along said sleeves and having openings for slidably receiving the sleeves so as to be guided by them, and a bucket supported by 45 said bail.

5. In a device of the type described, a supporting cable, a carriage movably supported thereby, a pair of guide cables depending from said carriage, a bucket movable along 50 said guide cables and being dischargeable to either side of the plane of its vertical movement, said guide cables being attachable to said carriage for lying in a plane at right angles to their former position.

55 6. A towerless hoisting and conveying device comprising a supporting cable, a carriage movably carried by said cable, guide cables depending from said carriage, anchoring means for said guide cables, a frame movable along said guide cables, means for raising and lowering said frame, a bucket movable along the length of said guide cables, means for moving said bucket, and means carried by said frame for receiving material 65 carried by said bucket.

7. A towerless hoisting and conveying device comprising a supporting cable, a carriage movable therealong and supported thereby, means for moving said carriage, guide cables depending from said carriage, material-receiving means adjustable along the length of said guide cables, and means movable along said guide cables for delivering material to said receiving means.

75 8. A towerless hoisting and conveying device comprising a supporting cable, a carriage movable therealong and supported thereby, guide cables depending from said carriage, material-receiving means adjustable along the length of said guide cables, 80 and a bucket movable along said guide cables for delivering material to said receiving means.

9. In a device of the type described, a supporting cable, a carriage movably supported 85 thereby, a pair of guide cables depending from said carriage, a bucket movable along said guide cables and being dischargeable to either side of the plane of its vertical movement.

90 10. In a device of the type described, a carriage, a pair of guide cables depending from said carriage, a bucket movable along said guide cables and being dischargeable to either side of the plane of its vertical movement, said guide cables being attachable to 95 said carriage for lying in a plane at right angles to their former position.

11. A towerless hoisting and conveying device comprising a pair of vertical guide cables, a carriage supporting the cables, supporting means for the carriage, a hopper adjustable along the length of said cables, a bucket movable along said cables, and means for raising and lowering said bucket to and 100 from the hopper.

12. A towerless hoisting and conveying device comprising a supporting cable, a carriage movable on said cable, vertical guide cables carried by said carriage and being adjustable along the length thereof, hoppers adjustable along the length of said vertical cables, and means movable along said vertical cables for conveying material to said 110 hoppers.

13. In a device of the type described, a supporting cable, a carriage mounted thereon, guide cables depending from said carriage, a plurality of hoppers, and a material-conveying means movable along the length 115 of said guide cables and being dischargeable into any one of said hoppers.

14. In a device of the type described, a supporting cable, a carriage mounted thereon, guide cables depending from said carriage, a frame adjustable along the length of said guide cables, a plurality of hoppers mounted on said frame and being disposed laterally of said guide cables, and a material-conveying means movable along the length of said 120 125 said guide cables.

guide cables and being dischargeable into any one of said hoppers.

15. In a device of the type described, a supporting cable, a carriage mounted thereon, a frame adjustable along the length of said guide cables, a plurality of hoppers mounted on said frame, and a material-conveying means movable along the length of said guide cables and being dischargeable into 10 any one of said hoppers.
